TRANSFER NEEDLE

Julius Sirmay, Philadelphia, Pa., assignor to The
Ordnance Gauge Company, Philadelphia, Pa.,
a corporation of Pennsylvania

Application August 9, 1947, Serial No. 767,748

9 Claims. (Cl. 66—95)

1

The present invention relates to certain new and useful transfer needle for knitting machine having two banks of needles and, more particularly, for circular knitting machine having a bank of dial needles and a bank of cylinder needles, and has for its object the more ready and more treadle-free transfer of stitches from one bank of needles to the other bank, when such transfer is desired for purposes of effecting certain variations in the knitted fabric.

In the prior-art of stitch-transfer mechanisms and transfer needles, the practice has been, among others, to provide a cam-surface on the side of the needle, over which the needle in the other needle-bank may ride (for the transfer operation), but in which the cam-surface, on the needle, is formed on the side of the needle by a bulge which is generally a counterpart of the cam-surface.

This required (among other things) the sacrificing of the continuous support of the needle, because of the necessity of eliminating the needle-guide slot (in the cylinder-bed or in the dial-bed) at a point beyond the position of such needle-carried cam in the retracted position of the needle, because the bulging side of the needle (where the cam is formed) cannot enter the needle-guide slot.

In other forms of stitch-transfer mechanisms of the prior-art, the needles were provided with spring-clips on the needles, attached to the sides of the needles, or extra jacks (having such spring-clip formation) were placed alongside of each needle, for the purpose of "opening" the stitch laterally in alignment with the needle of the other bank, so that the needle of such other bank could enter the loop so held open.

In the stitch-transfer machine of the present invention, each set of needles is formed with an upper needle-retaining recess and a lower needle camming recess in its side, with a stitch-retaining shoulder between these two recesses, whereby (when the one set or bank of needles is shifted or "racked" in relation to the other set or bank of needles, a distance of one-half of a needle-space, and the two sets or banks of needles thus brought into full alignment with each other) the needles from which the loops are to be transferred are first extended, and the receiving needles are thereafter extended into the upper recesses in the sides of the first set of needles (from which the loops are to be transferred), and held there in fixed position until the first set of needles (from which the loops are to be transferred) is extended forward so as to bring the needle in the camming

2

recess thereof into alignment with the receiving needles. In this position, the outer end of the loop is hung on the shoulder which is between the two recesses (on needle from which the loop is to be transferred) while the receiving needle then forces its way into the loop while it is so hung on such shoulder; as the receiving needle is extended further and beyond the camming surface; the so extended receiving needle being deflected or sprung partially by the camming surface of the needle from which the loop is being transferred. The receiving needle is held in this extended position until the full withdrawal of the needles from which the loop is being transferred, whereby such needles remove themselves from the loops or cast off the loops onto the needles of the other bank.

By means of the transfer-needle of my present invention, transfer-needles may be employed both in the dial-bed as well as in the cylinder-bed, whereas with the transfer-needles of the prior-art, which had spring-clips or other enlargements projecting from their sides, it was not possible either to utilize such transfer-needles in both banks, or, utilizing them in both banks, it was not possible to knit wholly on one bank of needles alone, because the fore-cut of the bed had to be cut down so far (in order to clear the spring-clip or other lateral projection of the transfer-needle) that there was not enough fore-cut remaining to support the yarn to form the next loop, as the needle was retracted. Thus, it was not possible to knit a plain jersey fabric type of knit-formation on such transfer-needles of the prior-art.

By means of the transfer-needle of the present invention, it is possible to use transfer-needles in both the cylinder and dial, and to transfer from cylinder to dial and from dial back to cylinder, and it is possible by my invention to transfer only some or all the loops from one bank to another, and if only some (rather than all) loops are transferred, then every third or fourth loop in the bank may be transferred or alternate pairs of loops may be transferred or any selected group of loops may be transferred according to any pattern. Likewise, it is possible, by means of my novel transfer-needle, to transfer from a loop-bearing transfer-needle of one bank to an open needle of the other bank and thereafter activate such needle of the other bank to which the loop was so transferred.

When the needles between which the transfer is to be effected are circumferentially spaced as, for instance, high-butts needles in the cylinder bed and high-butts needles in the dial bed, it is

necessary to bring the needles in alignment with each other for transfer. However, when the needles between which the transfer is to be effected are already in alignment with each other as, for instance, the high-butt needles in the one bank and the low-butt needles in the other bank, it is not necessary to "rack," in the transfer operation.

By the needle construction of the present invention, the needles are given full lateral support in their respective slots, because the needles are without any lateral projections or bulges, so that the slots guiding them need not be widened to clear the spring clips or bulges on the needles.

In the needle construction of my present invention, the receiving needle is caused to enter the receiving-recess of the needle from which the loop is to be transferred, by the timing of the two dwells of the needle-engaging or butt-engaging cams, while the point of the two dwells on such cams then causes the receiving needle to be extended still further in timed relation to the needle from which the loop is to be transferred. The receiving needle is caused to be extended to its outermost transfer position when the other needle has been extended so that the needle camming recess thereof is in alignment with the receiving needle.

Figure 1 represents a fragmentary side-elevational view of a transfer needle embodying my present invention, on an enlarged scale, shown in the cylinder position, with 4 positions of the hook of a cooperating dial-needle shown, in relation to the hook-retaining and hook-camming recesses in the side of the cylinder-needle.

Figure 2 represents a section, on line 2—2, of Figure 1, on still further enlarged scale.

Figure 3 represents a section of line 3—3, of Fig. 1, but also on a still further enlarged scale (the same scale as Figure 2).

Figure 4 represents a fragmentary vertical cross-sectional view of a cylinder bed and a dial bed, shown schematically, and with a transfer-needle of the present invention shown in the cylinder bed, and with a needle in the dial-bed shown in operative juxtaposition thereto, and generally in position 2 of Figure 1.

Figure 5 is a view, similar to Fig. 4, but with the needles in a position between position 3 and position 4 shown in Figure 1.

Figure 6 represents a view similar to that shown in Figures 1, 4 and 5, but with the needles in position 4 of Figure 1.

Figure 7 represents a view similar to that shown in Figures 4, 5, and 6, but with the positions of the needles in the next stage, namely, in the stage where the cylinder-needle has started moving down and has left the loop on the hook of the dial-needle.

Figure 8 represents a view similar to that shown by Figures 4, 5, 6 and 7 but with the cylinder-needle moved further down, and with its latch about to close, as its latch and hook withdraws from the loop which is then left behind on the dial-needle.

Figure 9 represents a view similar to that shown in Figures 4 to 8, inclusive, but with the hook of the cylinder-needle fully withdrawn from the loop.

Figure 10 is a view similar to that shown in Figures 4 to 9, inclusive, but with the dial-needle (carrying the transferred loop) fully withdrawn, and represents the last stage in the stitch transfer operation, wherein the dial-needle has been fully withdrawn from the path of the cylinder-

needle, and wherein the cylinder-needle is shown in its raised position for another course. In this stage, either a double loop is left on the receiving-needle, or the original loop may be cast off from the receiving-needle.

The transfer-needle of the present invention, as shown in the drawings, includes a hook-retaining recess 11 in one side of the needle just below the latch-carrying portion thereof, and a hook-camming recess 12 in the same side of the needle, just below the hook-retaining recess 11.

The hook-retaining recess 11 preferably is in the upper shallow part of the needle, while the hook-camming recess 12 is in the lower and deeper part of the needle, as shown in the drawings, and intervening these two parts in a loop-retaining and elevating shoulder 14, upon which the loop 15 is adapted to be engaged, when the needle from which the loop is to be transferred, advances further during the transferring operation.

The hook-retaining recess 11 preferably has an outer terminal wall 13 which is either at a right angle to the side faces of the needle or is slightly undercut as shown in Fig. 3. The side-wall 19 of recess 11 is preferably slightly inclined as shown in Fig. 3.

The side-wall 16 of the hook-camming recess 12, on the other hand, is gradually inclined from its starting edge 17 to its terminal edge 18, either along a straight or plane surface or along a slightly curved surface as indicated at 16, in Figure 2. The purpose of the gradual inclination of this surface 16, is gradually to force or "cam" the nose of the needle of the opposite bank (to which the loop is to be transferred) off to one side of the needle (from which the loop is to be transferred). This camming, to one side, into the position shown in Figure 2, is made possible by the resiliency or flexing of the needles.

The cycle or sequence of operational stages or operational positions, in a transfer, is generally as follows: Position 1, shown in Figure 1, indicates the relative positions of the dial-needle which is to receive the loop and the cylinder-needle which is to relinquish the loop, while the dial-needle is still stationary, and as the cylinder-needle is beginning its up-travel, but before the hook-retaining recess 11 has come into alignment with the dial-needle; this position 1 being in advance of the position shown in Figure 2.

Position 2, so designated in Figure 1, and also shown independently in Figure 4, is the next stage, and in which the cylinder-needle has traveled a bit further in its up-travel, to the position where the hook-retaining recess 11 of the cylinder-needle is in alignment with the dial-needle, and in which the dial-needle has advanced towards the cylinder-needle, so that its hook enters the hook-retaining recess 11 of the cylinder-needle.

As the cylinder-needle travels still further in its up-travel, it moves to the position (relative to the dial-needle) which is designated as position 3, in Figure 1 and then moves still further to the position shown in Figure 5, and finally into the position designated as "position 4" in Figure 1, and also shown in Figure 6, during which the dial-needle advances further after the camming-recess 12 of the cylinder-needle is brought into alignment with the dial-needle (both needles moving forward, as the dial-needle enters the camming recess 12, during which movement of the dial-needle, the dial-needle starts under the

yarn loop 16, which is suspended on the shoulder 14).

After it has reached the position generally designated as "position 4" in Figure 1 and also shown in Figure 6 (which is the full up-position of the cylinder-needle), the dial-needle remains stationary, in its extended position, while the cylinder-needle is then withdrawn, downwardly, or is moved through its down-travel, through the stages shown in Figures 7, 8 and 9.

Figure 7 shows the next stage, in which the cylinder-needle is descending, while the yarn-loop is being controlled by the dial-needle (which dial-needle is stationary, during this stage).

The cylinder-needle continues to descend, while the dial-needle remains stationary, and while the dial-needle controls and carries the loop, as shown in Figure 8, and in that position, the latch of the cylinder-needle closes, under the influence of the loop which encompasses both dial-needle and cylinder-needle, so that as the cylinder-needle descends still further into the position shown in Figure 9, it withdraws from the loop entirely and is clear of the yarn.

The same cycle of transfer stages may be then carried out upon the transfer from the dial-needle to the cylinder-needle.

The transfer-needle of the present invention not only has the advantage of greater facility in operation, but also has greater durability and greater accuracy in operation.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described my invention, what I claim as new and desire to protect by Letters Patent is:

1. A transfer-needle for two-bank knitting machines wherein stitches are transferred from needles of one bank to needles of the other bank, said transfer-needle comprising a hook-retaining recess in one side of the needle, and a hook-camming recess in the same side of the needle and adjacent to the hook-retaining recess and merging with it; the hook-retaining recess being nearer to the hook of the needle and having one surface thereof generally parallel with the side-surface of the needle and one surface thereof generally at a right angle to said side-surface, and the hook-camming recess being farther from the hook of the needle, and a loop-retaining shoulder extending laterally across the needle, in the front-edge thereof, approximately in alignment with a zone in which the hook-retaining recess merges into the hook-camming recess no portion of said needle protruding laterally beyond the planes of the side-surfaces of the shank of said needle.

2. A transfer-needle for two-bank knitting machines wherein stitches are transferred from needles of one bank to needles of the other bank, said transfer-needle comprising a hook-retaining recess in one side of the needle, and a hook-camming recess in the same side of the needle and adjacent to the hook-retaining recess and merging with it; the hook-retaining recess being nearer to the hook of the needle and having one surface thereof generally parallel with the side-surface of the needle and one surface thereof generally at a right angle to said side-surface, and

the hook-camming recess being farther from the hook of the needle, and a loop-retaining shoulder extending laterally across the needle, in the front-edge thereof, approximately in alignment with a zone in which the hook-retaining recess merges into the hook-camming recess; said loop-retaining shoulder being the full thickness of the needle no portion of said needle protruding laterally beyond the planes of the side-surfaces of the shank of said needle.

3. A transfer-needle for two-bank knitting machines wherein stitches are transferred from needles of one bank to needles of the other bank, said transfer-needle comprising a hook-retaining recess in one side of the needle, and a hook-camming recess in the same side of the needle and adjacent to the hook-retaining recess and merging with it; the hook-retaining recess being nearer to the hook of the needle and having one surface thereof generally parallel with the side-surface of the needle and one surface thereof generally at a right angle to said side-surface, and the hook-camming recess being farther from the hook of the needle, and a loop-retaining shoulder extending laterally across the needle, in the front-edge thereof, approximately in alignment with a zone in which the hook-retaining recess merges into the hook-camming recess; said loop-retaining shoulder being slightly above the hook-camming recess, no portion of said needle protruding laterally beyond the planes of the side-surfaces of the shank of said needle.

4. A transfer-needle for two-bank knitting machines wherein stitches are transferred from needles of one bank to needles of the other bank, said transfer-needle comprising a hook-retaining recess in the needle, and a hook-camming recess in the same side of the needle and adjacent to the hook-retaining recess and merging with it; the hook-retaining recess being nearer to the hook of the needle and having one surface thereof generally parallel with the side-surface of the needle and one surface thereof generally at a right angle to said side-surface, and the hook-camming recess being farther from the hook of the needle, and a loop-retaining shoulder extending laterally across the needle, in the front-edge thereof, approximately in alignment with a zone in which the hook-retaining recess merges into the hook-camming recess; said loop-retaining shoulder being slightly above the hook-camming recess, no portion of said needle protruding laterally beyond the planes of the side-surfaces of the shank of said needle.

5. A transfer-needle for two-bank knitting machines wherein stitches are transferred from needles of one bank to needles of the other bank, said transfer-needle comprising a hook-retaining recess in one side of the needle, and a hook camming recess in the same side of the needle and adjacent to the hook retaining recess and merging with it; the hook-retaining recess being nearer to the hook of the needle and having one surface thereof generally parallel with the side-surface of the needle and one surface thereof generally at a right angle to said side-surface, and the hook-camming recess being farther from the hook of the needle, and a loop-retaining shoulder extending laterally across the needle, in the front-edge thereof, approximately in alignment with a zone in which the hook-retaining recess merges into the hook-camming recess; said loop-retaining shoulder being slightly above the hook-camming recess, no portion of said needle protruding laterally beyond the planes of the side-surfaces of the shank of said needle.

6. A transfer-needle for two-bank knitting machines wherein stitches are transferred from needles of one bank to needles of the other bank, said transfer-needle including a recess in one side

of the needle, said recess having a hook-retaining portion and a hook-camming portion, said hook-retaining portion being nearer to the hook of the needle and having one surface thereof generally parallel with the side-surface of the needle and one surface thereof generally at a right angle to said side-surface, and said hook-camming portion being farther from the hook of the needle, said hook-retaining portion being fully open on the side of the needle, said hook-camming portion merging into said hook-retaining portion and extending farther across the side of the needle than the hook-retaining portion but emerging on the side of the needle somewhat short of the outer or front edge of the needle, a hook-guiding portion in the same plane as the side of the needle, a loop-retaining shoulder extending laterally across the needle in the front edge thereof, no portion of said needle protruding beyond the side-walls of the shank of said needle.

7. A transfer-needle for two-bank knitting machines wherein stitches are transferred from needles of one bank to needles of the other bank, said transfer-needle including a recess in one side of the needle, said recess having a hook-retaining portion and a hook-camming portion, said hook-retaining portion being nearer to the hook of the needle, and said hook-camming portion being farther from the hook of the needle, said hook-retaining portion having one surface thereof generally parallel with the side-surface of the needle and one surface thereof generally at a right angle to said side-surface of the needle and being exposed on one side of the needle, said hook-camming portion merging into said hook-retaining portion and extending farther across the side of the needle than the hook-retaining portion but emerging on the side of the needle somewhat short of the outer or front edge of the needle, a hook-guiding portion in the same plane as the side of the needle, a loop-retaining shoulder extending laterally across the needle in the front edge thereof approximately in alignment with the juncture zone between the hook-retaining portion and the hook-camming portion of said recess, no portion of said needle protruding beyond the side-walls of the shank of said needle.

8. A transfer-needle for two-bank knitting machines wherein stitches are transferred from needles of one bank to needles of the other bank, said transfer-needle including a recess in one side of the needle, said recess having a hook-retaining portion and a hook-camming portion, said hook-retaining portion being nearer to the hook of the needle, and said hook-camming portion being farther from the hook of the needle, said hook-retaining portion having one surface thereof generally parallel with the side-surface of the needle and one surface thereof generally at a right angle to said side-surface of the needle and being exposed on one side of the needle, said hook- 55
50
60

camming portion merging into said hook-retaining portion and extending farther across the side of the needle than the hook-retaining portion but emerging on the side of the needle somewhat short of the outer or front edge of the needle, a hook-guiding portion in the same plane as the side of the needle, a loop-retaining shoulder extending laterally across the needle in the front edge thereof approximately in alignment with the juncture zone between the hook-retaining portion and the hook-camming portion of said recess, no portion of said needle protruding beyond the side-walls of the shank of said needle; said loop-retaining shoulder being the full thickness of the needle.

9. A transfer-needle for two-bank knitting machines wherein stitches are transferred from needles of one bank to needles of the other bank, said transfer-needle including a recess in one side of the needle, said recess having a hook-retaining portion and a hook-camming portion, said hook-retaining portion being nearer to the hook of the needle, and said hook-camming portion being farther from the hook of the needle, said hook-retaining portion having one surface thereof generally parallel with the side-surface of the needle and one surface thereof generally at a right angle to said side-surface of the needle and being exposed on one side of the needle, said hook-camming portion merging into said hook-retaining portion and extending farther across the side of the needle than the hook-retaining portion but emerging on the side of the needle somewhat short of the outer or front edge of the needle, a hook-guiding portion in the same plane as the side of the needle, a loop-retaining shoulder extending laterally across the needle in the front edge thereof approximately in alignment with the juncture zone between the hook-retaining portion and the hook-camming portion of said recess, no portion of said needle protruding beyond the side-walls of the shank of said needle; said loop-retaining shoulder being slightly above the hook-camming portion of said recess.
